Primary Examiner — Wan Laymon(74) *Attorney, Agent, or Firm* — Richard M. Goldberg(57) **CLAIM**

The ornamental design for a heating moxa cautery apparatus, as shown and described.

DESCRIPTION

FIG. 1 is a perspective view of the heating moxa cautery apparatus of my design;

FIG. 2 is a front elevational view thereof;

FIG. 3 is a rear elevational view thereof;

FIG. 4 is a left side elevational view thereof, with the right side elevational view being a mirror image thereof;

FIG. 5 is a top plan view thereof;

FIG. 6 is a bottom plan view thereof;

FIG. 7 is a cross-sectional view thereof, taken along line 7-7 of FIG. 5; and,

FIG. 8 is a perspective view of a plurality of the design of FIG. 1, showing a state of attachment on a the skin of a person's hand.

The broken lines in FIG. 8 are included for the purpose of illustrating portions of the heating moxa cautery apparatus and form no part of the claimed design.
